UNITED STATES PATENT OFFICE.

WILLIAM R. STRICKLAND, OF CLEVELAND, OHIO, ASSIGNOR TO THE PEERLESS MOTOR CAR COMPANY, OF CLEVELAND, OHIO, A CORPORATION OF OHIO.

LUBRICATING SYSTEM FOR INTERNAL-COMBUSTION ENGINES.

1,384,873.

Specification of Letters Patent. Patented July 19, 1921.

Application filed September 16, 1918. Serial No. 254,272.

To all whom it may concern:

Be it known that I, WILLIAM R. STRICKLAND, a citizen of the United States, residing at Cleveland, in the county of Cuyahoga and State of Ohio, have invented a certain new and useful Improvement in Lubricating Systems for Internal-Combustion Engines, of which the following is a full, clear, and exact description.

10 This invention relates to internal combustion engines, and especially to the lubricating system thereof.

In one aspect, the invention relates to the oil pump which may be termed a double 15 pump, composed of three or more meshing gears, and adapted to receive oil from two sources or points of supply, and to deliver oil through two outlets.

In another aspect, the invention relates 20 to an engine of the so-called dry base crank-case having a tank constituting the principal source of supply, with generally no more oil in the crank-case than is constantly thrown off from the bearings, and in this connection 25 the invention comprises a lubricating system utilizing the double oil pump together with two inlet connections from the tank and sump of the crank-case, and two outlet connections, one leading to the bearings to 30 be lubricated and the other to the tank, the whole being so arranged that oil will be pumped from both the sump and the tank, keeping the crank-case practically clear of oil, and will be pumped to the bearings and 35 also by an independent passageway to the tank, the passage of oil to and from the pump being such that there is a tendency to maintain the crank-case clear of oil and also a tendency to maintain the tank filled, as 40 will be explained more in detail in the body of the specification.

The invention may be further briefly summarized as consisting in certain novel details of construction and combinations and 45 arrangements of parts which will be described in the specification and set forth in the appended claims.

In the accompanying sheet of drawings, Figure 1 is a side view of a portion of an 50 internal combustion engine equipped with my invention, parts being broken away; Fig. 2 is a view looking at the inside of the lower half of the crank-case; and Fig. 3 is a sectional view through the pump.

55 Referring now to the drawings, 10 repre-

sents the lower half of the crank-case of the engine, which aside from the details of the lubricating system may be of any construction having the usual crank-shaft which is indicated at 11, and the cam-shaft which 60 is indicated at 12.

At the lower rear end of the crank-case, and attached thereto by bolts, as is customary, is an oil pump 13, including a flanged gear housing 14 which is secured to 65 the crank-case. Ordinarily the housing of the pump contains two gears, receiving oil from one inlet and delivering through an outlet, but in this instance the housing contains three gears, 15, 16 and 17. The gears 70 16 and 17 are idler gears driven by the intermediate gear 15, to which is connected a vertical driving shaft 15^a which may be driven in any suitable manner, but preferably from the cam-shaft 12 through gearing 75 indicated conveniently at 15^b. As is customary, this shaft 15^a includes a lower part connected by a slip coupling 18 to the main upper portion so as to permit the ready removal of the pump, and in this instance the 80 lower part is inclosed in an upstanding tube 19, secured to the removable part of the pump and flanged at its upper end to permit the ready centering and coupling of the two parts. However, the manner of 85 driving the pump, and the method of fastening it to the crank-case are immaterial to my invention.

The housing of the pump has two inlets 90 designated in Fig. 3, 20 and 21, the inlet 20 receiving oil from the crank-case sump in any suitable manner, but in this case through a short pipe 22 (see Fig. 1) provided at its inlet end with a strainer 23, which may be of the conventional type. The other inlet 95 21 receives the oil from an oil supply tank 24, through a pipe 25 extending from the bottom of the tank and connected to a boss on the side of the pump housing 14. The tank 24 may be located at any point with 100 reference to the engine, and assuming that the system is utilized in connection with the engine of a motor vehicle, for which my invention is particularly adapted, the tank 24 may be supported on the vehicle at any convenient place, and at any suitable height 110 with respect to the engine.

The two outlets of the pump are indicated respectively at 26 and 27. The former leads to the bearings of the engine which are to be 105

lubricated, and in this instance, this outlet 26 includes a cored passageway 26^a extending beneath the gears of the pump, and a vertical passageway 26^b extending up through the wall of the crank-case structure, this latter being indicated in Figs. 1 and 2. The connection may be made between this passageway 26^b and the bearings to be lubricated in any suitable manner, the oil usually being conveyed from this passageway to the oil line of the crank-shaft. The second outlet 27, is connected to the top of the tank 24 by a pipe 28, suitably attached to a boss at the lower part of the pump. Additionally the system includes an overflow pipe 29 for the tank 24, this pipe extending from the top of the tank to the lower half of the crank-case as indicated in Fig. 1 and also in Fig. 2, which shows a portion of the overflow pipe.

This system operates in the following manner: When the engine is in operation, oil is drawn from the sump to the inlet 20 by the action of the gears 15 and 16, and at the same time it is drawn from the tank 24 to the inlet 21 by the action of the gears 15 and 17. At the same time oil is delivered by the pump through the outlet 26 to the bearings and through the outlet 27 back to the tank. But since there are unequal back pressures or heads opposing the flow through the outlet passageways, this being due to the restricted passageways through which the oil passes in its course to the various bearings to be lubricated, and due to the fact that there is a certain amount of leakage around the teeth of the pump gears, the flow of oil through the two outlets is unequal, a larger percentage of the oil passing to the outlet 27 and back to the tank, than to the outlet 26 leading to the bearings. For example, the oil entering at 20 from the sump passes part with the teeth of gear 16 to the outlet 27 leading to the tank, and part with the teeth of gear 15 to the outlet 26 leading to the bearings, but since the outlet for the passage leading to the bearings is closed except for small clearance openings in the bearings themselves, and by a relief valve which maintains a certain fixed pressure, the relatively large back pressure through this outlet as compared with the outlet leading to the tank causes a considerable leakage of oil around the teeth of the gear 15, which leakage increases as the wear on the pump parts increases. In consequence of the oil entering at 20, a larger percentage passes to the outlet 27 and to the tank than to the outlet 26 and to the bearings. Similarly, the oil entering at 21 from the tank passes part with the teeth of gear 17 to the outlet 26 leading to the bearings, and part with the teeth of gear 15 to the outlet 27 leading to the tank, and for the same reasons explained above, namely, because of the unequal back

pressures in the two outlets, and the leakage around the teeth, a greater percentage of this oil passes to the tank than to the bearings.

These two unbalanced deliveries of oil, due to the difference in pressures or back pressures, always maintain an unbalance in favor of the tank, this unbalancing in quantity being dependent on the clearance between the pump housing and the gear teeth. As a matter of fact, however, it is found that this pump operates in the manner explained, even when the pump is new and the fits are as close as a pump can be made to run without sticking. In such case, however, the time element required for emptying the sump if it is filled with oil at the start, is greater than after the clearance between the gears and the pump housing has increased, due to wear.

In other words, if a customer fills the tank and also the crank-case, this pump will maintain the tank full, and the consumption of oil will gradually lower the level of oil in the crank-case until it is empty, and after that will gradually lower the oil level in the tank until it also is empty. Or if the customer fills the tank and wishes to maintain a dry base crank-case, and starts without any oil in the crank-case, the pump will furnish oil from the tank to the bearings under pressure, and the oil then escaping to the sump will be immediately pumped back to the tank and bearings, the major portion passing to the tank, and the dry base will be maintained as the amount of oil which the pump is capable of handling from sump to tank will in all cases be greater than the amount of oil that the pump will handle from the tank to the bearings.

Having described my invention, I claim:

1. In combination with an engine having a crank-case, a lubricating system and a source of supply of oil separate from the sump of the crank-case, of a double pump comprising a housing and a plurality of gears including a driving gear adapted to be rotated by the engine, and two gears driven thereby, said housing having an inlet leading from the crank-case, a second inlet leading from said source of supply, and two outlets, one leading to the lubricating system and the other to said source of supply.

2. In combination with an internal combustion engine having a lubricating system and a crank-case receiving oil thrown off from the bearings, of a tank constituting a source of supply for oil adapted to be supplied to the lubricating system, and a pump comprising a housing having three gears, one meshing with another, said housing having two inlets, one extending from the crank-case and one from the tank, and two outlets, one adapted to supply oil to the lubricating system and the other to the tank.

3. In combination with an internal combustion engine having a lubricating system, of a source of supply for oil, and an engine driven pump for supplying oil to the lubricating system and comprising a chamber containing oil impelling means, said chamber having an inlet connection from said source an outlet connection to the lubricating system, and a second outlet connection to said source.
4. In combination with an internal-combustion engine having a lubricating system and a source of oil for said system, of an engine driven pump comprising a chamber containing oil impelling means, said chamber having an inlet connection from the crank-case of the engine, and an inlet connection from said source, and having an outlet connection to the lubricating system, and an outlet connection to said source.
5. In combination with an engine having a lubricating system and a receptacle adapted to supply oil thereto, of an engine driven pump comprising a chamber containing oil impelling means, said chamber having an inlet connection with said receptacle, and two outlet connections, one connected to the lubricating system and one leading back to said receptacle and adapted to convey to the receptacle the excess oil not delivered to the system.
6. The combination with an internal combustion engine having a lubricating system and an oil receptacle, of an engine driven pump comprising a chamber containing oil impelling means, said chamber having two inlets, one connected to the crank-case and one to the receptacle, and having an outlet connected to the lubricating system, said impelling means adapted to receive oil from both inlets and to deliver it to the outlet leading to the lubricating system.
7. The combination with an internal combustion engine having a lubricating system and an oil receptacle, of an engine driven pump comprising a chamber containing oil impelling means, said chamber having an inlet connected to the receptacle and two outlets, one connected to the lubricating system and the other to the receptacle, the impelling means serving to deliver part of the oil received from the inlet to one outlet, and part to the other outlet.
8. The combination with an internal combustion engine having a lubricating system and an oil receptacle, of an engine driven pump comprising a chamber containing oil impelling means, said chamber having two inlets leading respectively from the crank-case of the engine and from the receptacle, and having two outlets leading respectively to the lubricating system and to the receptacle whereby oil may be delivered by the impelling means from one inlet to both outlets, or from both inlets to each outlet.

In testimony whereof I hereunto affix my signature.

WILLIAM R. STRICKLAND.
